United States Patent Office.

MAX HOFFHEIMER, OF CINCINNATI, OHIO.

Design No. 4,004, dated May 3, 1870.

DESIGN FOR A BRAND.

The Schedule referred to in these Letters Patent and making part of the same

I, MAX HOFFHEIMER, of Cincinnati, in the county of Hamilton and State of Ohio, have invented and produced a new Design for a Brand or Label for Whisky-Barrels, of which the following is a specification.

The nature of my design is fully represented in the accompanying drawings, to which reference is made, but I do not wish to be understood as restricting myself to the precise words used on the brand or label.

Claim.

I claim as my invention, The design for a brand or label for barrels, substantially as shown and set forth.

In testimony of which invention I hereunto set my hand.

Witnesses: MAX HOFFHEIMER.
